(57) **CLAIM**

The ornamental design for a bed, as shown and described.

DESCRIPTION

FIG. 1 is a front perspective view of a bed showing our new design;

FIG. 2 is front view thereof;

FIG. 3 is a rear perspective view thereof;

FIG. 4 is a rear view thereof;

FIG. 5 is a left side view thereof, the right side view being a mirror image thereof;

FIG. 6 is a top view thereof;

FIG. 7 is a front perspective view of a bed showing a second embodiment of our new design;

FIG. 8 is front view thereof;

FIG. 9 is a rear perspective view thereof;

FIG. 10 is a rear view thereof;

FIG. 11 is a left side view thereof, the right side view being a mirror image thereof; and,

FIG. 12 is a top view thereof.

The broken lines represent portions of the bed that form no part of the claimed design.

1 Claim, 12 Drawing Sheets
